UNITED STATES PATENT OFFICE.

FRED LESLIE VILAS, OF PIERRE, SOUTH DAKOTA.

FOUNTAIN EYECUP.

Application filed September 11, 1925. Serial No. 55,742.

This invention relates to an improved medical appliance which may be conveniently designated as a fountain eye cup, or bathing device.

The invention has more particular reference to a new article of manufacture comprising a bottle containing the eye bathing fluid, an eye cup, and a connection between the cup and the neck of the bottle, whereby the contents of the latter may be conveniently discharged into the cup in the quantity desired.

In one embodiment, there is a stopper fitted into the neck of the bottle, and a tube connected thereto. The eye cup being carried on the outer end of the tube.

One feature is to provide a separable tube upon which the eye cup is mounted for rotation permitted to be disposed in the most convenient position for use by the individual.

Another feature of the invention is to provide a plunger valve for controlling the discharge of the fluid from the bottle into the cup.

Another object and feature is to provide a one piece rubber device comprising stopper, tube, and cup, the tube being compressible so that by placing the fingers upon the same, it can be squeezed to open and close as desired for feeding the fluid from the bottle into the cup.

Other features and advantages of the invention will become apparent from the following description and drawing.

In the accompanying drawing forming a part of this application and in which like numerals are employed to designate like parts throughout the same:

Figure 1 is a side view of a portion of a bottle showing the cup and connecting tube, a portion of the cup being shown in section to show the manner in which it is mounted.

Figure 2 is a similar view taken at an approximate right angle to Figure 1 showing the details in section to disclose the construction more plainly.

Figure 3 is a view somewhat like Figure 2 showing a different embodiment of the invention.

Referring to the drawings in detail, and especially to Figures 1 and 2, it will be seen that the bottle is designated by the reference character 1. In practice, the bottle will be somewhat rectangular in general configuration, but the top wall will be inclined

upon the approximate angle shown to facilitate dispensing of the eye fluid from the bottle. The reference character 2 designates the reduced flanged neck of the bottle. Fitted into this neck as shown plainly in Figure 2 is a cork stopper 3. Also fitted into the reduced central opening of the stopper is a metallic feed tube 4 preferably of aluminum or some light weight metal. It will be noted that the tube has its central bore of a diameter sufficient to permit free flow of the eye treating fluid from the bottle. Moreover, at its outer end it is provided with spaced flanges defining an annular groove 5. The eye cup 6 which is of rubber, has an opening formed in its bottom, and the edges of the opening are engaged between the flanges or confined in the groove 5 to rotatably connect the cup with the tube. The tube is of more or less conventional configuration. Fitted slidably into the tube and extending crosswise of the bore is a plunger 7 having an opening 8 formed therein adapted to register with said bore. A removable head 9 is carried by this plunger, and the head is formed with a skirt 10. This forms a cup for reception of one end of a coiled spring 11. The spring surrounds the projecting portion of the plunger and the inner end thereof bears against the tube 4. The spring serves to normally move the plunger outwardly to close the passage.

By pressing the plunger inwardly and aligning the bowl 8 with the passage in the tube 4, and by tilting the bottle slightly, the fluid will flow from the latter through the passage and into the cup to be used. Any desired amount of fluid may be emptied into the cup. The cup may be turned at an angle with respect to the bottle to conveniently position it for reception of the eye. It will be noted that the spring cup or skirt 10 limits the sliding movement of the plunger and assures proper alignment of the hole 8 with the passage.

Directing attention now to the embodiment of the invention shown in Figure 3, it will be seen that the bottle is designated by the reference character 12, the neck by the reference character 13. In this instance I provide a single rubber article comprising the eye cup 14, the tube 15, the plug 16 fitting into the neck of the bottle, and the stop flange 17. In this form of the invention there is no control valve. Instead, the tube

15 is of compressible rubber and is adapted to be grasped between the fingers of the hand and squeezed so that the hand may be utilized as a valve for cutting off the flow 5 of fluid.

It is believed that by considering the description in connection with the drawings, persons familiar with appliances of this 10 class will be able to obtain a clear understanding of the invention, its advantages, and various uses. Therefore a more lengthy description is deemed unnecessary.

While the preferred embodiments of the 15 invention have been shown and described, it is to be understood that minor changes coming within the field of invention claimed may be resorted to if desired.

Having thus described the invention, what I claim as new and desire to secure by 20 Letters Patent is:—

1. As a new article of manufacture, an eye treating appliance comprising a bottle

adapted to contain a medicine, said bottle including a discharge neck, a flanged stopper fitted into said neck, said stopper having a central passage, a tube connected with said stopper and communicating with said passage, and an eye cup at the outer end of said tube, said tube and cup being of rubber. 25

2. In an appliance of the class described, 30 in combination, a bottle adapted to contain an eye treating fluid, said bottle including a discharge neck, a stopper fitted into said neck and having a central bore, a tube having its inner end fitted into said bore and 35 provided at its outer end with longitudinally spaced annular flanges providing a groove therebetween, an eye cup having an opening, the edges of which are confined between said flanges, and a spring closed plunger 40 valve carried by the central portion of said tube.

In testimony whereof I affix my signature.
FRED LESLIE VILAS.
